EXPLOSION-PROOF ELECTRICAL CONNECTING DEVICE

Etienne Castelli, Paris, France, assignor to Société à Responsabilité Limitée dite: Arlux, Casablanca, Morocco

Application January 12, 1953, Serial No. 330,700

5 Claims. (Cl. 339—111)

This invention relates to electrical connecting device and more specifically to an explosion-proof plug-in device for connecting a general current supply or network to any electrical apparatus having fire-damp-proof features, notably safety lamps, etc. The device according to this invention may be connected and disconnected in a dangerous atmosphere without having to break the supply circuit. Besides, it is attached in a permanent manner to the supply wire of the apparatus.

This electrical connecting device comprises two parts, a female part or plug and a male part.

The plug is a socket made of light metallic or plastic material, closed at one end by a cap member and provided with a pair of lateral fittings with packing glands in view of forming a T connection with a supply cable, the assembly being completely fire-proof. The central portion of the aforesaid cap member is hollowed out to provide a passage for a bolt having a length greater than the socket and intended to secure the plug to the male part.

This socket encloses insulating bodies which fill it exactly, the rear body receiving a pair of elastic contacts and the front body having formed therein two passages for the contact pins; both insulating bodies are separated from each other by a movable disk adapted to be rotated about its center, its movements being controlled by the aforesaid bolt so as to obturate or uncover the contact pin passages.

The male part consists of a base on which are secured the contact pins and a sleeve portion of a length slightly greater than these contact pins; this sleeve portion is adapted to frictionally engage the outer wall of the front end portion of the plug socket, so as to insulate the contact pins from the outside and prevent them from being tampered with.

The base may be formed integrally with an internally screwed central boss for engagement by the aforesaid bolt.

When this bolt is screwed in, the male and female parts on the one hand and the contacts thereof on the other hand are caused to engage each other.

Other characteristic features and advantages of this electrical connecting device will appear more in detail hereafter with reference to the attached drawings illustrating by way of example one specific form of embodiment of the invention. In the drawings:

Figure 1 is a vertical axial section;

Figure 2 is a similar but fragmentary section showing the contacts in engagement;

Figure 3 is a vertical section according to the line III—III of Fig. 1;

Figures 4 and 5 are horizontal sections according to the lines IV—IV of Fig. 1 and V—V of Fig. 3 respectively.

Referring to the drawings, the socket element of the device consists of a generally cylindrical hollow member 6 made of fireproof, light-weight material; this member is closed at one end by a fluid-tight cap member 1 and formed with a pair of coaxial lateral fittings 21, 22 to provide for a "T" connection, each fitting having mounted therein a packing gland 7, as shown, for the lead-in wires. The central portion of cap member 1 is formed with a chambered hole 27 through which an assembling bolt 2 may be introduced. This bolt 2 is longer than the plug socket 6.

This socket encloses a pair of insulating bodies, a first body 12 through which the contact pins 23, 24 secured

to the lamp (or other electrical appliance or tool) may be inserted in a flame-proof manner, and another insulating body 20 which has fitted therein a pair of resilient contacts 9.

Between these insulating bodies is mounted for rotation in its plane about its center an insulating disk 10 adapted automatically to obturate both pin passages when the plug is released from the lamp or other electrical apparatus. Thus, any access to the resilient contacts is precluded when the plug is removed. This disk is rotated through a friction device 3 mounted on the shank of bolt 2. The latter constitutes at the same time a means for fixing the plug to the lamp.

The male portion of the device consists of a pair of contact pins 23, 24 carried by the base 15; a boss 19 formed integrally with this base is internally threaded to receive the threaded portion of bolt 2. In order to afford a clearer understanding of the degree of safety obtained with this device it is well to consider jointly the male and female parts thereof. It will be seen that when the current supply is established or broken, while the contact pins are still live, some clearance exists between the bottom of the plug (female part) and the base-forming casing. At that time it is still possible to contact the pins with a metal object and produce dangerous sparks.

To avoid this risk the base 15 is formed with a cylindrical extension 16 fast with the lamp with which the plug is designed to co-operate. With this cylindrical extension the contact pins cannot be tampered with. Moreover, it protects the pins against shocks when the movable plug is fully detached from the assembly. Finally, it acts as an anti-explosion shell.

Operation

It is assumed that the plug is connected to the supply network. Both contact pins 23, 24 are introduced into the relevant passages of the insulating member 12 and the plug is driven home, that is until the central boss 19 engages the end of bolt 2. By using an adequate spanner the latter is screwed into the boss 19 and as the contact pins are driven further into their corresponding passages they engage the movable disk 10, thereby releasing studs 11 fixed to this disk from corresponding cavities 31 formed in the insulating member 12. Thus, the disk 10, driven through the medium of the friction device 3 mounted on bolt 2 is rotated until it is stopped by the pair of distance-pieces 28 separating the insulating members 20 and 12 from each other. Under these conditions the disk is so positioned that a pair of holes 30, 31 formed therein are coaxial with the contact pins 23, 24. Thus, the latter will progress further into the plug and finally engage the pair of resilient contacts 9, thereby supplying current to the relevant apparatus or lamp. It will be noted that when the plug is being locked to the base the male and female parts of the device are already engaged to an extent such as to prevent the plug from being thrown away by an internal explosion.

To retract the plug, it is sufficient to repeat this operation in the reverse direction. The bolt 2 is unscrewed so that the contacts are gradually moved away from one another; when the contact pins are completely out from the holes in disk 10 the latter rotates in the opposite direction and when the stud 11 secured thereto registers with the corresponding hole formed in the insulating member 12 it engages the latter under the pressure exerted by the spring 5. Then, both pin passages in the insulating member 12 are obturated by the disk. Finally, the bolt is further unscrewed until the plug can be removed from the lamp or like apparatus.

To disconnect the device from the supply network it will be sufficient to release the screws 29 through which the cap member 1 is secured to the plug, so that this cap member can be removed with the bolt 2 therein. Thus, access may be had to the terminals 14 on which are secured the inlet wires which pass through the packing glands.

Although the foregoing is to be considered as the description of a typical and preferred embodiment of the invention, anybody conversant with the art will readily understand that many modifications may be brought thereto without departing from the spirit and scope of the invention.

What I claim is:

1. Anti-explosion connecting device for an electrical apparatus in a dangerous atmosphere, comprising a male part consisting of an insulating base, contact pins supported by said base, a cylindrical extension on said base surrounding said contact pins, a central, hollow, internally-threaded boss on said base, and a female part consisting of an insulating socket adapted to be frictionally engaged into said cylindrical extension of said base, a pair of superimposed insulating bodies within said socket, central holes in said insulating bodies and side passages in the front one of said insulating bodies for said contact pins of said male part of the device, resilient contacts in the rear one of said insulating bodies, a rotary disk arranged between said insulating bodies and formed with holes adapted to allow said contact pins therethrough, a cap member fixed to the rear end of said socket, a chambered hole in said cap member, an assembling bolt passing without clearance through said holes in said cap member and insulating bodies, and adapted to engage said internally-threaded boss of said male part, a pair of hollow fittings provided with packing glands and adapted to form a T connection with electric wires passing therethrough and fixed to terminal members of said resilient contacts, a stud-and-hole locking device adapted when the device is inoperative to maintain a solid portion of said disk in register with said contact pins, and means for frictionally driving said disk about its center when said disk-retaining stud is released by the engagement of said disk by said contact pins when said male and female parts are being assembled.

2. Explosion-proof plug-in device for an electrical apparatus in a dangerous atmosphere comprising a male part consisting of an insulating base, contact pins supported by the said base, a cylindrical extension forming part of the said base and surrounding the said contact pins, a central boss fixed to the base on the inside and a female part comprising an insulating socket adapted to be frictionally engaged into the said cylindrical extension of the male part, two insulating bodies rigidly fixed one below the other in the said socket and pierced by axial passages, the first insulating body being pierced moreover by channels in which the contact pins of the male part may be engaged, resilient contacts mounted in the other insulating body in line with said channels, a cap-member closing the socket and pierced by an axial passage, a rotating bolt imprisoned in the axial passage of the cap-member, passing through the axial passages of the two insulating bodies and terminating in an extremity adapted to be screwed into the boss of the male part, a disk mounted to be frictionally rotated around the bolt between the two insulating bodies and pierced with passage holes for the passage of the contact pins of the male part and locking devices for locking the disk in the position which closes the passages of the first insulating body until the disk is engaged by the contact pins.

3. Explosion-proof plug-in device, for an electrical apparatus in a dangerous atmosphere comprising a male part consisting of an insulating base, contact pins supported by the said base, a cylindrical extension forming part of the said base, and surrounding the said contact pins, a central boss fixed to the base on the inside and a female part comprising an insulating socket adapted to be frictionally engaged into the said cylindrical extension of the male part, two insulating bodies rigidly fixed one below the other in the said socket and pierced by axial passages the first insulating body being pierced, moreover, by channels in which the contact pins of the male part may be engaged, resilient contacts mounted in the other insulating body in line with said channels, two coaxial lateral fittings to provide for a "T" connection on both sides of the socket for the lead-in wires to be connected to the contacts, fluid-tight packing-glands mounted in the coaxial lateral fittings, a cap-member closing the socket and pierced by an axial passage, a rotating bolt imprisoned in the axial passage of the cap member, passing through the axial passages of the two insulating bodies and terminating in an extremity adapted to be screwed into the boss of the male part, a disk mounted to be frictionally rotated around the bolt between the

5 two insulating bodies and pierced with passage holes for the passage of the contact pins of the male part and locking devices for locking the disk in the position which closes the passages of the first insulating body until the disk is engaged by the contact pins.

10 4. Explosion-proof plug-in device, for an electrical apparatus in a dangerous atmosphere comprising a male part consisting of an insulating base, contact pins supported by the said base, a cylindrical extension forming part of the said base and surrounding the said contact pins, a central boss fixed to the base on the inside and a female part comprising an insulating socket adapted to be frictionally engaged into the said cylindrical extension of the male part, two insulating bodies rigidly fixed one below the other in the said socket and pierced by axial passages the first insulating body being pierced, moreover, by channels in which the contact pins of the male part may be engaged, resilient contacts mounted in the other insulating body in line with said channels, a cap-member closing the socket and pierced by an axial passage, a rotating bolt imprisoned in the axial passage of the cap-member, passing through the axial passages of the two insulating bodies and terminating by an extremity adapted to be screwed into the boss of the male part, a disk mounted to be rotated around the bolt between the two insulating bodies and pierced with passage holes for the passage of the contact pins of the male part, studs mounted in the disk and adapted to fit into the holes of the first insulating body by locking the disk in such a position as to close the channels, resilient devices fixed around the bolt pushing the disk against the first insulating body and engaging the studs in the holes until the disk is engaged by the contact pins when the female part is placed in position by screwing the bolt into the boss of the male part and a friction device which, when the disk has been unlocked by the pushing of the contact pins following the rotating movement of the bolt, brings it to a position in which the contact pins pass through the passage holes.

15 5. Explosion-proof plug-in device, for an electrical apparatus in a dangerous atmosphere comprising a male part consisting of an insulating base, contact pins supported by the said base, a cylindrical extension forming part of the said base and surrounding the said contact pins, a central boss fixed to the base on the inside and a female part comprising an insulating socket adapted to be frictionally engaged into the said cylindrical extension of the male part, two insulating bodies rigidly fixed one below the other in the said socket and pierced by axial passages the first insulating body being pierced, moreover, by channels in which the contact pins of the male part may be engaged, resilient contacts mounted in the other insulating body in line with said channels, a cap-member closing the socket and pierced by an axial passage, a rotating bolt imprisoned in the axial passage of the cap-member, passing through the axial passages of the two insulating bodies and terminating by an extremity adapted to be screwed into the boss of the male part, a disk mounted in the disk and adapted to fit into the holes of the first insulating body by locking the disk in such a position as to close the channels, resilient devices fixed around the bolt pushing the disk against the first insulating body and engaging the studs in the holes until the disk is engaged by the contact pins when the female part is placed in position by screwing the bolt into the boss of the male part and a friction device which, when the disk has been unlocked by the pushing of the contact pins following the rotating movement of the bolt, brings it to a position in which the passage holes are opposite the contact pins and the distance pieces fixed in the two insulating bodies thus immobilizing the disk in this position during the passage of the contact pins until the bolt is completely screwed up.
